(57) **CLAIM**

The ornamental design for a breath mint dispenser, as shown and described.

DESCRIPTION

FIG. 1 is a front, right side perspective view of a breath mint dispenser made in accordance with my new design;

FIG. 2 is a front view of the embodiment of FIG. 1;

FIG. 3 is a back view of the embodiment of FIG. 1;

FIG. 4 is a top plan view of the embodiment of FIG. 1, with the bottom plan view being the mirror image of the top plan view;

FIG. 5 is a left side elevational view of the embodiment of FIG. 1; and,

FIG. 6 is a right side elevational view of the embodiment of FIG. 1.

(Stippling is used in the Figures to show surface contour and is not representative of texture).

1 Claim, 2 Drawing Sheets
